UNITED STATES PATENT OFFICE

CHRISTOPHER A. SCHELLENS, OF MARBLEHEAD, MASSACHUSETTS, ASSIGNOR TO C-S ENGINEERING COMPANY, OF ENGLEWOOD, NEW JERSEY, A CORPORATION OF DELAWARE

TENDER-FEED-WATER HEATER

Application filed August 11, 1928. Serial No. 298,946.

This invention relates to improvements in feed water heaters and particularly to heaters located in locomotive tenders for heating the feed water of locomotives by direct contact with a heating medium.

One of the primary objects of my invention is the provision of a tender feed water heater of the character described in which pollution of the water in the tender and difficulties incident thereto are prevented.

Another object of my invention is the provision of a feed water heater of the character described in which gases and the like, as well as oil and the like, are effectively removed or permitted to escape from the tender, thus greatly increasing the efficiency of the heater itself and ensuring effective performance of the entire feed water system.

More specifically stated, it is an object of my invention to provide a device of the character described in which oil is collected and flushed out of the tender every time that the tender is filled with water.

A more specific object is the provision of a novel combined vent, overflow means and collector for oil and the like for tender feed water heaters.

My invention also contemplates certain detail improvements and combination of parts in heaters of the class described as will hereinafter appear.

How the foregoing, together with such other objects and advantages as may herein-after appear, or are incident to my invention, are realized, is illustrated in preferred form in the accompanying drawings, wherein—

Fig. 1 is a fragmentary longitudinal section through a portion of a locomotive tender showing my invention applied thereto, certain of the parts appearing in elevation.

Fig. 2 is a fragmentary plan section taken on the line 2—2 of Fig. 1.

Fig. 3 is an enlarged sectional view taken on the line 3—3 of Fig. 1, and

Fig. 4 is a view similar to Fig. 1 illustrating a modification of my invention.

Referring now more particularly to Figs. 1 to 3 inclusive, I have illustrated my improved feed water heater A in a preferred

location, namely, at the front portion of a locomotive tender B and in association with the water withdrawal mechanism C of the tender which may be of any suitable construction.

The water heater A comprises, in general, a heater casing 5, a nozzle device 6 for heating the water by direct contact with a heating medium, an overflow pipe 7, and means 7a receiving the overflow of the pipe 7.

In the form illustrated in Figs. 1 and 2 the heater casing 5 is preferably of sheet metal construction and rectangular in form, two sides and the bottom of the casing being formed in this instance by the tender. This casing is preferably of small volumetric content as compared to the volumetric content of the tender and provides a chamber for separating a portion of the water in the tender from the remainder thereof, there being, however, constant communication between said portions of water through an opening 8 in the lower portion of the casing. The casing is located over the water withdrawal mechanism C and may be said to be a hood for such mechanism.

The nozzle device 6 in this instance is in the form of a detachable member or casting adapted to be secured to the casing 5, as by means of bolts 9, over the opening 8 above referred to. This member is provided with an elongated nozzle chamber 10 having an inlet opening 11 for the introduction of a heating medium thereto, preferably exhaust steam, and also having a plurality of nozzle openings 12 in the lower curved portion thereof through which the steam is discharged.

Plugs 13 are provided at the ends of said chamber for cleaning out or other purposes. Extending downwardly from the ends of said chamber are a pair of legs 14 and extending forwardly from the chamber to the casing 5 is a wall 15, from which it will be seen that this nozzle device provides a passageway through which water must pass to enter the interior of the heater casing 5, for withdrawal through the water withdrawal orifice of the tender. In passing through this passageway the water is brought into direct contact with the steam discharging

through the nozzle openings 12 and is, therefore, heated, the steam being entrained with the flowing water.

A pipe line 16 leading from the source of steam supply conducts the steam to the nozzle chamber 10. I prefer to employ as the heating medium exhaust steam and condensate from a primary feed water heater located on the locomotive, although it is to be understood that if the tender heater is not associated with such a primary heater, as would be the case where the tender heater is used alone as the locomotive feed water heater, I may employ exhaust steam from the locomotive cylinders or from other steam operated appliances on the locomotive or both. The steam line 16 may be provided with suitable check and drain valves as desired.

Reverting now to the heater casing 5, it will be seen that the overflow pipe 7 hereinbefore mentioned extends upwardly from the top of the casing and terminates a short distance below the top plate 17 of the tender, the point of termination being substantially at the highest level of the water in the tank. Associated with the overflow pipe and located adjacent is termination is the means 7a above referred to for receiving the overflow of the pipe. This means is preferably in the form of a casing providing a closed chamber preventing entrance of water thereinto directly from the tender, the casing, in this instance, comprising a metallic body portion 18 and a readily detachable cover plate 19. Leading from the bottom of the body portion 18 is a drain pipe 20 discharging to the outside of the tender. This closed chamber is vented as by means of the vent pipe 21 provided in the cover plate 19. By providing the vent pipe 21 siphoning of the tender through the drain pipe 20 is also prevented.

The advantages of the arrangement just described will be understood from the following.

When heating water by direct contact with a heating medium in the manner above set forth, there are present air and non-condensable gases, as well as oil and the like. Unless provision is made to the contrary the effectiveness not only of the heater itself, but of the entire feed water system would be impaired and even be destroyed because of the inability of the pump to function.

I have found that by providing the heater device with a vent as disclosed in my copending application, Serial No. 119,630, filed June 30, 1926, the difficulties arising from the presence of air and non-condensables are overcome. In constructions made in accordance with said application it has been found that oil carried into the heater would overflow from the vent pipe and either lodge on the walls of the tender tank or pollute the water in the tank. In my present invention this objectionable feature is overcome by permitting

the oil accumulating in the vent pipe to escape to the exterior of the tender. In the preferred form of my invention the oil overflows into the collector means 7a in which the oil collects and from which it is discharged through the drain pipe 20. Thus the overflow pipe 7 serves the double purpose of permitting the escape of air from the heater casing and of permitting the escape of oil therefrom. In this connection it is pointed out that every time the tender is filled above the tank top, that is to say, that when the water level rises in the usual coaming provided around the filling opening, the oil in the pipe 7 will be flushed out. It will be seen from the foregoing that I have provided simple and effective means for carrying off oil and the like from the heater device without siphoning off water, for the oil, being lighter than the water in the overflow pipe, rises and eventually the head of oil reaches the top of the pipe and overflows, particularly every time the tender is filled.

While I have described the collector means 7a as providing a chamber closed against entrance of water directly from the tender, I also contemplate merely having the vent pipe extend to the exterior of the tender or other arrangements such as providing collector means in the form of a cup associated with the overflow pipe, in which case the upper edge of the cup would extend above the highest level of water in the tank so as to prevent the oil from overflowing from the cup and polluting the water in the tender.

Referring now to the modification of my invention shown in Fig. 4, it will be noted that the heater casing and nozzle device are of modified construction. In this form the heater casing 5a and the nozzle device 6a are integral. The nozzle chamber 10a is formed in the casing and extends only part way around the casing and is spaced somewhat above the floor of the tender. The remaining portion of the casing extends to the floor of the tender so that water can only enter the casing through the space below the chambered portion 10a. A plurality of nozzle openings 12a are provided in the rounded bottom of the chamber 10a, through which openings the heating medium discharges directly into the water passing to the interior of the casing 5a through the passageway provided by spacing the chamber 10a above the floor of the tender.

While I have shown the heating devices located over the water withdrawal orifice of the tender, I may, if desired, locate the heater device elsewhere in the tender and lead the water heated thereby to the water withdrawal orifice as by means of a pipe. In Fig. 4 I have illustrated a covered opening 22 available for such purpose. On removing the cover from this opening a pipe may be attached to the casing for leading the water to the with-

drawal orifice. In other respects the arrangement of Fig. 4 is similar to that shown in Fig. 1.

I claim:—

1. A locomotive feed water heater for tenders comprising, in combination, a heating device in the tender for heating water by direct contact with a heating medium, and means for carrying off oil and the like from said device including a riser pipe having an overflow chamber closed against discharge into the tender, and a drain for said chamber discharging to the outside of the tender.

2. A locomotive feed water heater for tenders comprising, in combination, a heating device in the tender for heating water by direct contact with a heating medium, an overflow pipe for said heating device, a closed casing receiving the overflow of said pipe, a vent for said casing, and a drain for said casing discharging to the outside of the tender, said overflow pipe, closed casing, and drain cooperating when the tender is being filled to constitute means for flushing oil and the like to the outside of the tender.

3. The combination with a heater device for heating locomotive feed water, said device being located within a locomotive tender, of a combined vent and overflow means for said heater device, said means including a pipe and a casing closed against discharge into the tender located at the discharge end of said pipe to receive the overflow thereof.

4. The combination with a heater device for heating locomotive feed water, said device being located within a locomotive tender, of a combined vent and overflow means for said heater device, said means including means for receiving the overflow thereof, said last mentioned means having a drain discharging to the outside of the tender and said first and second mentioned means cooperating when the tender is being filled to constitute means for flushing oil and the like to the outside of the tender.

5. The combination with a heater device for heating locomotive feed water, said device being located within a locomotive tender and having means for heating the water by direct contact with a heating medium, of an overflow pipe therefor, and a vented chamber located to receive the overflow of the overflow pipe, said chamber having a drain pipe leading to the outside of the tender, and said overflow pipe, vented chamber and drain pipe cooperating to constitute means for flushing oil and the like to the outside of the tender when the tender is being filled.

6. A locomotive feed water heater for tenders having a water withdrawal orifice, comprising, in combination, a casing within

the tender of small volumetric content relative the volumetric content of the tender, said casing being so located relative to the tender withdrawal orifice that the orifice is in communication with the interior of the casing and said casing having constant communication with the water in the tender, means for admitting a heating medium into the water as it enters the casing, an overflow pipe for said casing, a closed chamber into which the overflow pipe discharges, a vent for said chamber, and a drain for said chamber.

7. A locomotive feed water heater for tenders having a water withdrawal orifice, comprising, in combination, a heating device within the tender located adjacent the floor thereof, and in association with the water withdrawal orifice, said device including a casing the interior of which is in constant communication with the water in the tender, means for heating water as it enters the casing by direct contact with a heating medium, a second casing within the tender located adjacent the top of the tender, said second casing being closed against entrance of water thereinto directly from the tender, an overflow pipe for the first mentioned casing in communication with the second mentioned casing and discharging its overflow thereinto, a vent for said last mentioned casing, and a drain therefor.

8. A locomotive feed water heater for tenders having a water withdrawal orifice, comprising a heating device within the tender so located relative to said orifice that the orifice is in communication with the interior of the heating device, an overflow pipe for the heating device, said overflow pipe terminating substantially at the highest level of the water in the tender, and means extending above said water level for receiving the overflow from the overflow pipe.

In testimony whereof I have hereunto signed my name.

CHRISTOPHER A. SCHELLENS.
